UNITED STATES PATENT OFFICE.

FRED LACEY, OF LOWELL, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,362,116.

Specification of Letters Patent. Patented Dec. 14, 1920.

Application filed November 14, 1919. Serial No. 337,993.

To all whom it may concern:

Be it known that I, FRED LACEY, a citizen of the United States, and a resident of Lowell, in the county of Middlesex and State 5 of Massachusetts, have invented an Improvement in Feeler Mechanisms for Looms, of which the following description, in connection with the accompanying drawings, is a specification, like characters on the drawings representing like parts.

This invention relates to feeler mechanisms for looms, and more particularly to that type of feeler mechanism wherein the detecting element or feeler is given a movement longitudinally of the shuttle when the filling is substantially exhausted on a detecting beat.

One of the objects of the present invention is to provide a feeler mechanism of the general type indicated, wherein the means for effecting movement of the feeler longitudinally of the shuttle when filling is substantially exhausted on a detecting beat, is placed under tension by engagement with a part 25 carried by the lay on each detecting beat. This feature of the invention is carried into practical effect in the present instance by means of a feeler controller which may engage the shuttle on its detecting beat and 30 which is jointed to a member yieldingly connected to the feeler. The member between the controller and the feeler is formed as a lever, one end of which is connected to the controller and the other end of which 35 preferably extends rearwardly and is connected to the feeler by a spring which is tensioned by movement of the controller on each detecting beat.

The above and other novel features and 40 combinations of parts constituting the present invention will best be understood from the following description and accompanying drawings of one good practical form of the invention.

45 In the drawings:

Figure 1 is a perspective view of the feeler side of a loom, some of the parts being omitted because they are not intimately associated with the feeler mechanism;

50 Fig. 2 is an enlarged plan view showing the action of the feeler mechanism when a working supply of filling is present in the shuttle on a detecting beat;

Fig. 3 is a view similar to that of Fig.

2 showing the action of the feeler mechanism 55 when the filling is substantially exhausted on a detecting beat;

Fig. 4 is a cross section on the line 4—4 of Fig. 2.

The loom frame 1 has secured thereto 60 the brackets 2, one at each side of the loom in which is mounted the transverse or rock shaft 3 which may be of usual construction. Rising from the rock shaft 3 is the arm 4 having pivoted thereto at 5 the latch 6 65 which, when filling is substantially exhausted on a detecting beat, may be moved frontwardly by an operating member to rock the transverse or rock shaft 3 and thereby effect replenishment of filling, as usual in this 70 class of looms.

In the present instance the operating member consists of the cam follower 7 or a part connected thereto having a slide 8 which enters a recess or opening 9 in the end of 75 the latch 6. Extending transversely of the latch 6 and normally positioned at one side of the opening 9 is the bunter 10 adapted to slide transversely of the latch in a suitable bearing 11 associated therewith. 80

The loom frame, or preferably the shipper stand 12, has an extension 13 of usual character to which may be adjustably secured the feeler stand 14 by means of the clamping bolt 15, or other suitable clamping 85 means.

The feeler stand 14, in the present instance, provides bearings for a controller 16. These bearings may be variously formed and are conveniently provided by the upstanding front and rear lugs 17 and 18 formed on a plate 19 which may be secured to the feeler stand. Each of the lugs 17 and 18 is provided with an opening through which extends the controller 16 with freedom for 95 reciprocating movement therein. A spring 20 is interposed between the bearings 17 and a shoulder or pin 21 formed on or projecting from the controller 16, and the spring normally acts to hold the controller in its rearward position, as indicated in Fig. 1, but with permissive movement frontwardly when engaged by a part carried by the lay on a detecting beat. The plate 19 may be connected to the feeler stand 14 by means 100 of the bolts 22, Figs. 2 and 3, which extend through a slot 23, whereby adjustment of the controller to properly engage a part 105

carried by the lay on each detecting beat may be accomplished.

Pivotedly mounted on the feeler stand 14 at 24 is the feeler carrier 25 on which the feeler 26 is mounted for relative movement toward and from the front of the loom. Rising from the feeler carrier 25 are the front and rear bearing portions 27 and 28, respectively, through openings in which the feeler 26 extends. A spring 29 interposed between the front bearings 27 and a stop or pin 30 secured to the feeler member 26, serves normally to maintain the feeler 26 in its rearward feeling position. The above construction of the feeler carrier and the associated feeler provides a good practical form of means for permitting the feeler to be moved in a direction longitudinally of the shuttle. The feeler 26 is provided with teeth 31 on its rear end portion, which enter the shuttle on each detecting beat and feel for the filling therein. These teeth may be differently formed, the essential being that when they detect a working supply of filling in the shuttle they will sink into the filling on a detecting beat and restrain movement of the feeler longitudinally of the shuttle, but when filling is substantially exhausted on a detecting beat they will slip along the surface of the filling carrier longitudinally thereof.

Mounted on the feeler stand 14 at 32 is a lever which is independent of the feeler. One arm 33 of the lever extends laterally and is provided with an opening or slot 34 through which passes a pin 35 extending from the controller 16, the construction being such that upon movement of the controller toward or from the front of the loom, the lever will be moved upon its pivotal mounting. The other arm 36 of the lever extends rearwardly from the pivot 32 and has connected to its rear end a rod 37. The rod 37 is jointed to the rear end of the lever 36 by a pin 38 which passes through the head portion 39 of the rod and is properly held in place by a nut 40, as indicated in Fig. 4.

The present invention contemplates that the rear end portion of the lever arm 36 shall have yielding connection with the feeler and in the present instance of the invention this is effected by a spring 41 surrounding the rod 37 and having one end bearing against a shoulder 42 and the other end against a collar 43 loosely mounted upon the rod 37. The rod 37 extends through an opening 44 in a lug or flange 45 projecting upwardly from the feeler carrier 25 and is provided with a head or stop 46, the construction being such that upon movement of the rear end 36 of the lever from the dotted to the full line position, Fig. 2, when the feeler is restrained from its movement longitudinally of the shuttle, the spring 41 will be compressed and placed under tension, and such tension will be transmitted to the feeler through the connec-

tions described, the rod 37 at such times being pushed laterally through the opening 44 of the feeler carrier.

The feeler is connected to the bunter 10 by means of a rod 47, one end of which is jointed at 48 to the upstanding flange or lug 45 mounted on the feeler carrier, the construction being such that should the feeler be moved longitudinally of the shuttle, the rod 47 will be moved to place the bunter 10 in the path of movement of the slide 8, Fig. 1, and thereby effect forward movement of the latch 6 and rock the transverse shaft 3 to effect replenishment of filling.

Should the feeler be moved in the manner stated to effect replenishment of filling, it is desirable that the feeler be returned to its normal feeling position, as indicated in Fig. 1, as the lay goes back. This is effected in the present instance by means of the setting stop 46 on the rod 37, which, as the rear end portion 36 of the lever hereinbefore described, is moved to the left in the dotted line position, Fig. 2, engages the flange 45 and pulls the feeler into its normal feeling position.

The lay 49 may be of usual construction and provided with an opening 50 in its front wall which coincides with an opening 51 formed in the adjacent wall of the shuttle 52 and registering with the opening 50 when the shuttle is properly boxed at the detecting-side of the loom.

When a working supply of filling is present in the shuttle on a detecting beat, the feeler 26 enters the shuttle and the teeth 31 thereof sink into the filling. The controller 16 then engages a part carried by the lay, preferably the shuttle wall, and is moved forwardly thereby. The forward movement of the controller 16 effects a rocking movement of the lever from the position indicated in dotted lines to the position indicated in full lines, Fig. 2, and thereby tensions the spring 41 which tends to move the feeler in a direction longitudinally of the shuttle. Owing to the presence of a working supply of filling, however, the feeler is restrained from responding to the tension of the spring 41. When the filling is substantially exhausted on a detecting beat, the feeler 26 will again contact with the surface within the shuttle and the controller 16 will likewise be engaged and moved forwardly by the shuttle. The forward movement of the controller acting through the lever thereupon tensions the spring 41, as before, and effects movement of the feeler in a direction longitudinally of the shuttle, as indicated in Fig. 3. This movement of the feeler is transmitted through the rod 47 to the bunter 10 which is thus placed in the path of the slide 8 on the operating member to set in action the train of mechanism for replenishing filling. As the lay goes back and releases

the controller to rearward movement under the action of its spring 20, the pin 35 acting upon the lever arm 33 returns the lever to its dotted line position, Fig. 1, thereby pulling upon the rod 37 and causing the stop 46 to return the feeler to its initial feeling position.

Claims:

1. In a feeler mechanism for looms, the combination of a feeler mounted for movement in a direction longitudinally of the shuttle and held from such movement on a detecting beat by engagement with the filling until substantial exhaustion thereof, a feeler controller arranged to be engaged and moved frontwardly by the shuttle on each detecting beat, and a lever having one arm connected to the controller and another arm yieldingly connected to the feeler tending to move the feeler in a direction longitudinally of the shuttle when the controller is moved frontwardly.

2. In a feeler mechanism for looms, the combination of a feeler mounted for movement in a direction longitudinally of the shuttle and held from such movement on a detecting beat by engagement with the filling until substantial exhaustion thereof, a feeler controller arranged to be engaged and moved frontwardly by the shuttle on each detecting beat, a lever connected to the controller, and a spring interposed between the lever and feeler and placed under tension by the frontward movement of the controller to move the feeler longitudinally of the shuttle when the filling is substantially exhausted on a detecting beat.

3. In a feeler mechanism for looms, a feeler pivotally mounted to move in a direction longitudinally of the shuttle and held from such movement on a detecting beat by engagement with the filling until substantial exhaustion thereof, a feeler controller arranged to be engaged and moved frontwardly by the shuttle on each detecting beat, a lever pivoted independent of the feeler, a connection between the controller and one arm of the lever for swinging the lever on its pivot on each detecting beat, and a yielding connection between the feeler and the other arm of the lever tending to move the feeler longitudinally of the shuttle when the controller is moved frontwardly on a detecting beat.

4. In a feeler mechanism for looms, a feeler pivotally mounted to move in a direction longitudinally of the shuttle and held from such movement on a detecting beat by engagement with the filling until substantial exhaustion thereof, a feeler controller arranged to be engaged and moved frontwardly by the shuttle on each detecting beat, a lever pivoted independent of the feeler, a positive connection between the controller and one arm of the lever for swinging the

lever on its pivot as the controller is moved frontwardly and rearwardly, and a spring between the lever and feeler placed under tension by swinging movement of the lever as the controller moves frontwardly and 70 tending to move the feeler longitudinally of the shuttle on each detecting beat.

5. In a feeler mechanism for looms, the combination of a feeler mounted for movement longitudinally of the shuttle and held 75 from such movement on a detecting beat by engagement with the filling until substantial exhaustion thereof, a feeler controller arranged to be engaged and moved frontwardly by the shuttle on each detecting 80 beat, a spring for returning the controller to rearward position, a lever one arm of which is connected to the controller and the other arm of which is yieldingly connected to the feeler and tends to move the feeler 85 longitudinally of the shuttle when the controller moves frontwardly, and a setting stop connected to the lever for returning the feeler to feeling position when the controller moves rearwardly.

6. In a feeler mechanism for looms, the combination of a feeler mounted for movement longitudinally of the shuttle and held from such movement on a detecting beat by engagement with the filling until substantial 95 exhaustion thereof, a feeler controller arranged to be engaged and moved frontwardly by the shuttle on each detecting beat, a spring for returning the controller to rearward position, a lever mounted independent 100 of the feeler, means for connecting one arm of the lever to the controller for positively turning the lever by frontward and rearward movement of the controller, a rod connected to the other arm of the lever and 105 slidably connected to the feeler, a spring interposed between the feeler and said other arm of the lever arranged to be placed under tension by frontward movement of the controller and tending to move the feeler 110 longitudinally of the shuttle on each detecting beat.

7. In a feeler mechanism, the combination of a pivotally mounted feeler carrier, a feeler yieldingly mounted on the carrier, a controller arranged to be engaged and moved frontwardly by the shuttle on each detecting beat, a spring for returning the controller to rearward position, a lever having one end connected to the controller to cause 120 movement of the lever as the controller is moved either frontwardly or rearwardly, a rod connected to the other end of the lever, a lug on the feeler carrier through which the rod loosely extends, a stop head on the rod, 125 a spring between said other end of the lever and feeler carrier which is placed under tension by frontward movement of the controller.

8. In a feeler mechanism for looms, the 130

combination of a feeler mounted for movement longitudinally of the shuttle and restrained from such movement on a detecting beat by engagement with the filling until 5 substantial exhaustion thereof, a controller arranged to be engaged and moved frontwardly by a part on the lay on each detecting beat, a spring for returning the controller to rear position, a lever having one

arm connected to the controller, and a longer 10 rearwardly extending arm yieldingly connected to the feeler and tending to move it longitudinally of the shuttle when the controller is moved frontwardly.

In testimony whereof I have signed my 15 name to this specification.

FRED LACEY.
